UNITED STATES PATENT OFFICE.

CHARLES L. DEPOLLIER, OF BROOKLYN, NEW YORK.

WATCH.

1,322,547.

Specification of Letters Patent. Patented Nov. 25, 1919.

Application filed February 1, 1919. Serial No. 274,440.

To all whom it may concern:

Be it known that I, CHARLES L. DEPOLLIER, a citizen of the United States, residing in the borough of Brooklyn of the city of New York, in the State of New York, have invented certain new and useful Improvements in Watches, of which the following is a specification, reference being had to the accompanying drawing, forming a part 10 hereof.

The greatly increased use, during the war, of watches with luminous dials has disclosed the fact that such watches cease, after a lapse of time, to have the degree of accuracy which has proved to be essential. After careful investigation it has been found that the loss of accuracy is due in large measure to the gradual disintegration of the luminous material applied to the dial and 15 the penetration of the very fine dust created thereby into the watch movement. The very great convenience of the luminous watch dial has made it desirable to discover, if possible, some way in which the advantage 20 of the self-illuminated watch dial can be retained without the disadvantage of the loss of accuracy due to the cause just stated. It is therefore the object of this invention to provide means whereby the advantage of 25 the self-illuminated dial shall be retained without permitting the dust from the disintegrated material to penetrate the movement. In accordance with the invention the problem is solved by providing the watch 30 with a double crystal and applying the luminous material to the proximate face of one of the two crystals so that the luminous material is at all times completely inclosed between the two crystals and the particles 35 thereof cannot find their way into the movement, while at the same time the desired luminosity is retained. The invention will be more fully explained hereinafter, with reference to the accompanying drawing in 40 which it is illustrated, and in which—

Figure 1 is a face view of a watch with the bezel and crystals removed.

Fig. 2 is a view in section of the watch

shown in Fig. 1, but on a larger scale, the movement being omitted.

Fig. 3 is a face view of the inner crystal shown in Fig. 2.

Fig. 4 is a view similar to Fig. 2 but showing a modification.

The watch case may be constructed of any suitable material and in any suitable manner except so far as is necessary to permit two crystals to be secured in place over the ordinary dial. In the watch shown in the drawings the center *a* supports the usual dial *b* and the hands *c*. It is provided, at *a'*, with a seat for the reception of an inner crystal *d* which is shown as secured in a metal ring *d'*. The center *a* also receives a bezel *e* which is shown as threaded upon the center, and in the bezel *e* is seated in the usual manner an outer crystal *f*. The dial *b* has marked thereon, in usual manner and preferably in dull black, the usual figures, as at *b'*. Upon that surface of one of the two crystals *d*, *f* which is proximate to the other crystal, are formed of luminous material corresponding figures *d'*.

It is obvious that the crystals may be variously secured in place and that the figures of luminous material might be formed upon either crystal. In the modification shown in Fig. 4 the inner crystal *d'* is seated in the bezel *e*, as at *d'*, while the outer crystal *f* is seated in the bezel in the same manner as shown in Fig. 2. The figures *f'* of luminous material in this instance, however, are formed on the inner face of the outer crystal *f*.

It will be noted that the luminous material which forms the figures is completely inclosed between the two crystals and that, no matter how much the material may become disintegrated in the course of time, the particles thereof cannot work their way into the movement of the watch. At the same time the self-illuminated quality of the watch is retained. The figures formed of the luminous material are themselves visible in the dark and they serve also to illuminate the dial *b* and the figures *b'* thereon. The

watch therefore retains the desired luminous quality while it is not liable to lose accuracy by reason of the penetration of particles of the luminous material into the movement of 5 the watch.

I claim as my invention:

1. A watch having two crystals, one outside the other, and luminous material applied to the proximate face of one of the 10 crystals.

2. A watch having two crystals, one outside the other, and having figures formed of luminous material on the proximate face of one of the two crystals, the luminous material being thereby inclosed in the space between the two crystals. 15

This specification signed this 27th day of January, A. D. 1919.

CHARLES L. DEPOLIER.
